CONTROL MECHANISM

**Knud J. Helsing, Springfield, Mass., assignor to
Westinghouse Electric Corporation, East Pitts-
burgh, Pa., a corporation of Pennsylvania**

Application September 21, 1946, Serial No. 698,485

4 Claims. (Cl. 318—466)

1

This invention relates to control mechanism and particularly to mechanism which controls the operation of a device through a predetermined series of operations and then is rendered inoperative until an operator initiates operation of the mechanism by some predetermined means.

More specifically, an object of the invention is to provide a control mechanism, such as a coin-initiated mechanism, which, upon the insertion of a suitable coin, will cause operation of a device, for example, a vending machine, through a predetermined cycle of operations and which is so constructed and arranged that no repeated cycle of the machine will occur in the event the coin becomes lodged on the cycle-initiating switch, or if, for any reason, this switch fails to open after the coin has passed it.

While reference has been made in the foregoing paragraph to a coin-operated switch for initiating the cyclic operation of the machine, that switch may equally well be closed manually or by some other means than a coin.

An object of the invention is to provide a control mechanism having the aforesaid characteristics.

Another object is to provide a simple and efficient structure which may be applied to the shaft of, and is operated by the main timer motor.

Still another object is to provide a mechanism which automatically places the machine in normal operating condition when the fault has been cleared.

These and other objects are effected by the invention as will be apparent from the following description and claims taken in connection with the accompanying drawings, forming a part of this application, in which the figure is a schematic perspective view of a timer mechanism embodying the invention.

The invention is here shown as applied to a timer comprising a shaft 10 driven by a motor M. The shaft will carry a plurality of cams (not shown) adapted to contact switches in sequential order to operate the machine controlled by the timer through a predetermined cycle when operation of the timer motor is initiated by a predetermined act. At the end of the cycle, the timer breaks its own motor circuit and leaves the timer in condition for operation through a succeeding similar cycle on the repetition of the predetermined act, which may be the insertion of a coin in a slot or the operation of a push button.

The shaft 10 carries a cam 11 rotatable therewith which, at the end of the cycle, contacts a switch member 12 to separate contacts 13, 14 and

2

deenergize motor M. Thus when the machine is idle, contacts 13 and 14 are open and motor M is inactive. The motor is started by the momentary closing of switch 15 which is in parallel with switch member 12. The momentary closing of switch 15 may be caused by the passage of a coin through a chute 15a or the pressing of a push button or by other means. This switch is closed only momentarily, but sufficiently long to rotate motor M far enough to release cam 11 from switch member 12, whereupon contacts 13 and 14 engage to complete a holding circuit for motor M until the shaft 10 has rotated far enough to again bring cam 11 in contact with member 12 and thus 15 separate contacts 13, 14.

Under some conditions, momentary contact switch 15 may fail to open as intended, due to the lodging of a coin on the switch, the sticking together of the contacts or for other reasons. Under this condition, the machine controlled by the timer will continue to function, for example, to dispense articles, even though no additional coins are inserted. It is to prevent this unauthorized repeated cycling that the present invention is directed.

To this end, the shaft 10 carries a disc member 16 rotatable therewith. A finger 17 is loosely mounted on the shaft and disc 16 and is permitted to move between the limits defined by spaced pins 18, 19 mounted on the disc. A solenoid relay comprising a coil 20 and an armature 21 pivoted at 21a are provided and disposed adjacent the disc 16. The armature 21 carries a pair of contacts 22, 23 which may be mounted on leaf springs 24 and 25, respectively. The springs 24, 25 are so disposed that the contacts 22, 23 are normally closed and these contacts in turn are in series with the circuit through motor M. The spring member 25 projects a sufficient distance 40 beyond spring member 24 so that it may be engaged by the finger 17 under certain conditions to separate the contacts 22, 23. The armature 21 may also carry an additional spring member 26 carrying a contact 27 which is engaged by a contact 28 carried on the opposite side of the spring member 25 when the contacts 22, 23 are separated. The contacts in Fig. 1 are in the positions just described. Contacts 27, 28 may be in series with a signalling device, such as a light 29, to 45 indicate the machine is out of order, or they may also control the breaking of the primary circuit to the vending machine, or both. The armature 21 is normally biased away from the coil 20 about pivot 21a by a spring 30 and is restrained by a stop 30a.

3
Coil 20 is disposed in series with momentary contact switch 15 and with switch member 12, and as these switches are connected in parallel, the coil is deenergized only when both those switches are open. The cam 11 and disc 16 are so disposed on the shaft that contacts 13, 14 are separated just before contacts 22, 23 are separated by finger 17. The latter condition prevails, of course, only if the coil 20 remains energized after the contacts 13, 14 are separated and 10 due to the fact that, for some undesired reason, the switch 15 has not opened of its own accord.

The operation of the mechanism is believed apparent from the foregoing description. However, a brief résumé will be given. In the inactive position of the vending machine, switches 12 and 15 are open, contacts 22 and 23 are engaged, and coil 20 is deenergized. The finger 17 is in the dotted line position of Fig. 1. When switch 15 is closed, as by its momentary contact with a coin, motor M is energized, as is relay coil 20. Initial rotation of the motor is sufficient to move cam 11 beyond switch member 12 so that contacts 13, 14 are closed and the motor continues to rotate while various other cams carried 20 thereby cause the desired operation of the controlled machine.

At the end of a single revolution of shaft 10, cam 11 engages switch member 12 to separate contacts 13, 14, thus deenergizing motor M and coil 20. Thereupon the spring 30 pulls armature 21 out of the path of finger 17 and the latter drops to its dotted line position against pin 19. If, for any reason, however, the momentary contact switch 15 has failed to open as expected, the coil 20 will remain energized, and, contacts 22, 23 remaining closed, the motor will continue to cycle until finger 17 has engaged spring 25 to separate contacts 22, 23, thus deenergizing the motor and preventing further cycling of the machine until the source of trouble at switch 15 has been cleared up. When this has been done, the coil 20 becomes inactive and the machine is ready for normal operation. Likewise, when contacts 22, 23 are opened by finger 17, contacts 27, 28 are simultaneously closed to give a visual or audible signal of the condition of the machine and/or to also interrupt, through suitable circuits, the primary circuit to the machine.

While the invention has been shown in but one form, it will be obvious to those skilled in the art that it is not so limited, but is susceptible of various changes and modifications without departing from the spirit thereof.

4
What is claimed is:

1. In an electrically operated and controlled timing device, an electric motor, a rotatable shaft driven by the motor, said motor being adapted to be connected to a source of electric energy, switch means adapted to be momentarily closed for connecting the motor to the energy source, means associated with the rotatable shaft for maintaining the motor energized to rotate the driven shaft through a complete revolution after the motor has been initially energized by the momentarily closed switch means, a relay connected in series with the last-named switch means, a normally closed switch disposed in series with the momentarily closed switch means, said normally closed switch being controlled by said relay, and means responsive to the movement of said rotatable shaft for causing said normally closed switch to open and thereby break the circuit to the motor in the event the momentarily closed switch has failed to open upon the completion of one revolution of the driven shaft.

2. In an electrically operated and controlled timing device, an electric motor, a rotatable shaft driven by the motor, said motor being adapted to be connected to a source of electric energy, switch means adapted to be momentarily closed for connecting the motor to the energy source, means associated with the rotatable shaft for maintaining the motor energized to rotate the driven shaft through a complete revolution after the motor has been initially energized by the momentarily closed switch means, a relay connected in series with the last-named switch means, a normally closed switch disposed in series with the momentarily closed switch means, said normally closed switch being controlled by said relay, and means carried by said rotatable shaft for causing said normally closed switch to open and thereby break the circuit to the motor in the event the momentarily closed switch has failed to open upon the completion of one revolution of the driven shaft.

3. Structure according to claim 2 in which the said relay is connected in parallel with the motor and is energized simultaneously therewith.

4. Construction according to claim 2, in which the relay comprises a stationary coil and a movable armature, and contact members movable by said armature to a position adjacent the shaft when the aforesaid coil is energized.
